UNITED STATES PATENT OFFICE.

EDWIN B. MALMROS, OF LYNNBROOK, NEW YORK.

FLOTATION OF ORES.

Application filed December 30, 1920. Serial No. 434,071.

To all whom it may concern:

Be it known that I, EDWIN B. MALMROS, a subject of the King of Sweden, residing at Lynbrook, in the county of Nassau, 5 State of New York, have invented certain new and useful Improvements in the Flotation of Ores; and I do hereby declare the following to be a full, clear, and exact description of the invention, such as will enable others skilled in the art to which it 10 pertains to make and use the same.

This invention relates to the concentration of ores by flotation, and has for its object the provision of an improved flotation 15 apparatus.

In the flotation processes of ore concentration, a body of ore pulp is subjected to appropriate treatment to produce a floating mass of mineral-laden gas bubbles from 20 which the desired mineral concentrate is obtained. The grade of the concentrate is determined by the percentage of metalliferous matter therein as compared with the amount of gangue matter therein, and it is, of 25 course, desirable to attain as high a grade of concentrate as is consistent with satisfactory practice in other respects, such, for example, as the percentage of recovery of the metalliferous material. Where a considerable amount of gangue material is carried up into the floating mass of mineral-laden gas bubbles, the grade of the resulting 30 concentrate is very likely to be low, and this is especially true in the pneumatic flotation 35 process. The present invention aims particularly to improve or raise the grade of a flotation concentrate, and, in the improved apparatus of the invention, this aim is accomplished by causing the floating mass of 40 mineral-laden gas bubbles to move over the surface of a relatively quiescent liquid medium into which particles of gangue drop from the floating mass and are returned to the body of ore pulp undergoing the flotation 45 treatment.

The present invention is more particularly applicable to the pneumatic flotation process, since in this process a very considerable amount of gangue is carried into the 50 floating mass of gas bubbles (or bubble column) along with the metalliferous matter, so that the grade of the resulting concentrate is to a large extent determined by the selective action taking place in the mass or column of 55 gas bubbles, as a result of which this mass or column of gas bubbles is progressively

richer in mineral particles from the bottom to the top thereof. In the improved apparatus of the present invention, the mass or column of gas bubbles resulting from the 60 pneumatic flotation process is caused to move over the surface of a relatively quiescent liquid medium which is in communication with the main body of ore pulp undergoing the flotation treatment. During the 65 movement of the mass or column of gas bubbles over this quiescent liquid medium, a selective cleaning action takes place as a result of which a very considerable quantity of gangue particles drop from the mass or 70 column of gas bubbles into the liquid medium and are returned to the main body of ore pulp. In this manner, a very material enrichment in mineral matter takes place in the mass or column of gas bubbles, as a consequence of which a higher grade of concentrate 75 is obtained.

The principle of operation and novel features of the apparatus of the invention will be better understood from the following description taken in conjunction with the accompanying drawing, illustrating a pneumatic flotation cell embodying the invention. In this drawing:

Fig. 1 is a transverse section of the flotation cell;

Fig. 2 is a longitudinal section of the flotation cell and

Fig. 3 is a plan view of the flotation cell.

Referring now particularly to the accompanying drawing, the apparatus therein illustrated is a flotation cell of the pneumatic type. As represented in the drawing, the cell has a substantially flat bottom 5, and upwardly and outwardly inclined side walls 6, at the upper end of which are provided the longitudinal concentrate launders 7. The bottom 5 of the cell may be substantially horizontal, or, if desired, the bottom may have a slight downward inclination 95 from the feed end towards the tailings discharge end.

Appropriate means are provided for introducing into the cell a suitable gaseous flotation agent, such as air. Such means 105 may take various forms, and in the construction illustrated in the accompanying drawing, a plurality of gas or air compartments 8 are associated with the bottom 5 of the cell. Each air compartment 8 is provided with a porous medium 9, such as canvas, through which air, or other appropriate

gas, may be introduced in a finely disseminated state into the ore pulp. Each compartment 8 is connected by a valved pipe 10 with the air or gas main 11. By this arrangement the supply of air or other gaseous flotation agent to each compartment 8 may be independently controlled.

Two vertical baffles or partitions 12 are longitudinally mounted within the flotation 10 cell. The baffles 12 are arranged substantially above the longitudinal or side walls of the compartments 8 whereby the upwardly rising stream or current of gas bubbles passing through the porous media 9 is confined between the baffles 12, and a relatively quiescent zone is provided in the spaces between the baffles 12 and the side walls 6. The tops of the baffles 12 are slightly below the normal operating liquid level of the ore 20 pulp, while the bottoms of the baffles are spaced from the bottom of the cell to provide an appropriate communication between the relatively quiescent zones (between the baffles and the side walls of the apparatus) 25 and the active aeration zone (between the baffles 12).

In operating the apparatus illustrated in the drawing, in accordance with the principles of the present invention, the ore pulp 30 is fed into the apparatus at the end of the cell between the inclined feed baffle 13 and the adjacent end wall of the cell. The tailings are discharged from the cell through the tailings discharge outlet 14. The rate 35 of the tailings discharge is controlled in the usual manner by a float ball 15 and cooperating mechanism so as to maintain the liquid level of the ore pulp in the apparatus at the desired height. Air, or other appropriate 40 gas, is introduced through the porous media 9 in a finely disseminated state into the body of ore pulp between the baffles 12 and produces a supernatant or floating mass or column of mineral-laden gas bubbles in 45 the well understood manner. As a result of the arrangement of the baffles 12, substantially no gas bubbles find their way into the longitudinal space between the baffles 12 and the side walls 6, and accordingly the 50 liquid in these longitudinal spaces is in a relatively quiescent state. The floating mass or column of mineral-laden gas bubbles moves outwardly in either direction and passes over the surface of the relatively 55 quiescent liquid in the longitudinal spaces between the baffles 12 and the inclined side walls 6. During the passage of the mass or column of gas bubbles across these relatively quiescent zones, gangue particles drop 60 from the mass of air bubbles into the liquid in the quiescent zones and are returned beneath the bottoms of the baffles 12 into the active flotation zone of the apparatus. In this manner, a selective cleaning of the mass 65 or column of mineral-laden gas bubbles

takes place over the aforementioned quiescent zones and a richer or higher grade concentrate flows into the launder 7 than in pneumatic flotation apparatus of the heretofore customary types.

The apparatus of the invention possesses many features of superiority over the heretofore customary types of pneumatic flotation cells. In the first place, as a result of the enrichment of the concentrate, it is possible to produce in one cell or apparatus a concentrate of satisfactory grade, thus eliminating the retreatment of concentrates and the use of rougher and cleaner cells now generally practiced. Moreover, the invention permits the use of a larger volume of air (or other appropriate gas) per square foot of air-mat without blowing over and carrying into the final concentrate an objectionable percentage of gangue. Consequently, a higher air pressure can be employed in effecting the flotation operation and on this account a flat (or substantially flat) bottom cell can be employed without danger of blinding the porous medium. Moreover, the cross currents produced in the ore pulp by the arrangement of the longitudinal baffles have a tendency to clean the top surface of the porous medium, and finally, the circulation around the baffles provides for a retreatment of particles once floated and returned to the active flotation zone through the agency of the relatively quiescent zones.

From the foregoing description, it will be seen that in the improved apparatus of the invention the flotation concentration involves the following three (3) steps, (1) the formation of a column or mass of mineral-laden (both metalliferous and gangue) gas bubbles, (2) a cleaning of this column or mass of gas bubbles while passing over a relatively quiescent liquid medium, in the course of which a relatively considerable proportion of the gangue particles and a relatively much smaller percentage of the metalliferous particles (carried upwardly into the mass of gas bubbles by the flotation treatment) are permitted to drop into the liquid medium, and (3) the return of the mineral matter (both gangue and metalliferous), which falls into the quiescent liquid medium, to the main body of ore pulp and its retreatment there. Thus, the mass or column of mineral-laden gas bubbles produced by the flotation treatment undergoes a selective cleaning operation during its movement across the surface of the relatively quiescent liquid medium. By a selective cleaning action, I mean that during the passage of the mass or column of gas bubbles over the surface of the quiescent liquid medium, a relatively large proportion of gangue particles (as compared with metalliferous particles) drops from the moving mass or column of

gas bubbles into the liquid medium. Accordingly, a much higher or richer grade of concentrate is withdrawn from the apparatus than can be obtained in the absence of the selective cleaning step of the invention, and to this extent the flotation operation as a whole is materially improved.

I claim:—

1. An apparatus for the concentration of ores by flotation comprising an elongated chamber, means at one end of the chamber for feeding ore pulp thereto, means for maintaining a longitudinal flow of ore pulp through the chamber, a longitudinal froth-forming zone, a froth overflow extending along the length of the chamber, a longitudinal non-froth-forming zone over which the froth is caused to pass from the froth-forming zone to the froth overflow whereby certain portions of the ore are released from the froth in the non-froth-forming zone and are carried by the longitudinally flowing ore pulp to a point farther along into the froth-forming zone for retreatment.
2. An apparatus for the concentration of ores by flotation comprising an elongated chamber, means at one end of the chamber

for feeding ore pulp thereto, means for maintaining a longitudinal flow of ore pulp through the chamber, means for generating mineral laden gas bubbles over a longitudinal area including a portion only transversely of the surface area, a froth overflow extending along the length of the chamber, a longitudinal launder adjacent to the chamber, means for moving the column of mineral-laden gas bubbles immediately upon formation in a substantially lateral direction towards the launder to subject the column of gas bubbles to a selective cleaning action by passage laterally over the remaining longitudinal surface of the ore pulp thereby permitting certain portions of the ore to return to the longitudinally flowing ore pulp and to be carried farther along into the chamber for retreatment, said chamber having outwardly inclined side walls to facilitate the return of said certain portions of the ore to the longitudinally flowing ore pulp.

In testimony whereof I affix my signature.

EDWIN B. MALMROS.
